UNITED STATES PATENT OFFICE.

CHARLES SNYDER, OF FAIR MOUNT, NEW YORK.

HOLDBACK.

SPECIFICATION forming part of Letters Patent No. 325,573, dated September 1, 1885.

Application filed July 6, 1885. (No model.)

To all whom it may concern:

Be it known that I, CHARLES SNYDER, of Fair Mount, in the county of Onondaga in the State of New York, have invented new and useful Improvements in Holdbacks for Harness, of which the following, taken in connection with the accompanying drawings, is a full, clear, and exact description.

This invention consists of a metallic holdback for harness, which holdback is easily adjusted in length, readily connected to the harness, and is perfectly secure and stronger and more durable than the ordinary leather straps heretofore used for that purpose.

15 The invention is fully illustrated in the annexed drawings, wherein Figure I shows my improved metallic holdback in its connection with the thills and harness. Fig. II is a detached enlarged side view of the holdback, 20 and Fig. III is a top view of the same.

Similar letters of reference indicate corresponding parts.

25 *a* and *a'* represent two metallic straps provided, respectively, with a series of perforations, *b b*, distributed over the lengths of the straps. Said straps are spliced together adjustably lengthwise by a T-shaped lug, *c*, attached to the splicing end of the strap *a'*, and standing transversely thereon. By turning 30 said strap to a right angle from the other strap, *a*, the lug *c* is adapted to enter one of the perforations *b* of the latter strap, and protrude with its head through the same. In swinging the strap *a'* back into line with the other strap, the head of the T-lug *c* locks the straps together. A clamping-screw, *s*, passing 35 through one of the perforations *b* of the strap *a'*, and engaging a screw-threaded eye, *f*, on the strap *a*, serves to retain the straps in line 40 with each other.

The strap *a* is provided at its end with an eye, *e*, by which it is connected to a hook or staple, *t*, secured to the thills, as represented in Fig. I of the drawings. The opposite end of the other strap, *a'*, has formed integral with it a snap-hook, *d*, by which the holdback is connected with the usual ring, *r*, of the breeching.

Having described my invention, what I claim as new, and desire to secure by Letters Patent, is—

50 1. A holdback for harness composed of metallic straps spliced together adjustably lengthwise, as set forth.

2. The combination of the metallic strap *a*, provided with perforations *b b*, the metallic strap *a'*, provided with the T-lug *c*, and the clamping-screw *s*, substantially as described and shown.

3. In combination with the metallic strap *a*, the metallic strap *a'*, spliced adjustably on the strap *a*, and the snap-hook *d*, formed integral with the end of the strap *a'*, substantially as described and shown.

4. In combination with the breeching of the harness and the hook or staple *t* on the thills, 65 the metallic strap *a*, provided with the eye *e*, the metallic strap *a'*, spliced adjustably on the strap *a*, and the snap-hook *d* on the end of the strap *a'*, substantially as described and shown.

In testimony whereof I have hereunto signed 70 my name and affixed my seal, in the presence of two attesting witnesses, at Syracuse, in the county of Onondaga, in the State of New York, this 19th day of June, 1885.

CHARLES SNYDER. [L. S.]

Witnesses:

FREDERICK H. GIBBS,
MATTHEW J. DOLPHIN.
